BUS STOP SHELTER

Peter R. Hollaender, 2206 Raeburn Drive,
Cincinnati, Ohio

Filed Aug. 31, 1962, Ser. No. 71,514

Term of patent 14 years

(Cl. D13—1)

FIG. 1

FIG. 2

I claim:

The ornamental design for a bus stop shelter, substantially as shown.
